CLAIM

The ornamental design for a fly fishing reel, as shown and described.

DESCRIPTION

FIG. 1 is a perspective view of a fly fishing reel showing the new design;

FIG. 2 is another perspective view of the reel of FIG. 1 with the spool disassembled from the frame;

FIG. 3 is a first side view of the reel shown in FIGS. 1 and 2;

FIG. 4 is a front view of the reel shown in FIGS. 1-3;

FIG. 5 is a second side view of the reel shown in FIGS. 1-4;

FIG. 6 is a rear view of the reel shown in FIGS. 1-5;

FIG. 7 is a bottom view of the reel shown in FIGS. 1-6; and, FIG. 8 is a top view of the reel shown in FIGS. 1-7.

The broken line showing of environment in the drawings is for illustrative purposes only and forms no part of the claimed design.
